[57] CLAIM

The ornamental design for a chair, as shown and described.

DESCRIPTION

FIG. 1 is a perspective view of a chair showing my new design;

FIG. 2 is a top plan view thereof;

FIG. 3 is a front elevational view thereof;

FIG. 4 is a right side elevational view thereof, the left side view being a mirror image of that shown; and,

FIG. 5 is a rear elevational view thereof.

The bottom surface of the chair is not part of the design sought to be patented and is therefore not shown.
